UNITED STATES PATENT OFFICE.

HENRY RAZNY, OF DETROIT, MICHIGAN, ASSIGNOR OF ONE-THIRD TO JULIA LASKOWSKA, OF DETROIT, MICHIGAN.

DESIGN FOR A TOY.

47,011.

Specification for Design.

Patented Feb. 23, 1915.

Application filed October 14, 1914. Serial No. 866,720. Term of patent 14 years.

To all whom it may concern:

Be it known that I, HENRY RAZNY, a subject of the Czar of Russia, residing at Detroit, in the county of Wayne and State of Michigan, have invented a new, original, and ornamental Design for Toys, of which the following is a specification, reference being had to the accompanying drawings, forming part thereof.

The figure is a perspective view of a toy, showing my new design.

Copies of this patent may be obtained for five cents each, by addressing the "Commissioner of Patents, Washington, D. C."

I claim:

The ornamental design for a toy, as shown.

In testimony whereof I affix my signature in presence of two witnesses.

HENRY RAZNY.
